CONCEALABLE APPAREL RACK FOR CLOSETS

Stanley M. Friedenreich, New Hyde Park, N. Y.

Application February 6, 1956, Serial No. 563,480

6 Claims. (Cl. 20—1.11)

This invention relates to what I term a concealable rack adapted to be mounted in connection with garment closets for support of various types and kinds of apparel in raised and substantially concealed position at the upper portion of a closet. Further, my invention deals with supporting brackets for the rack secured to the upper portion of the closet and including means for maintaining the rack in substantially concealed position at the top of the closet while, at the same time, permitting the rack to be lowered to the front opening of the closet for accessibility to the articles supported upon the rack.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a diagrammatic perspective view of a corner portion of a closet, illustrating one of my improved racks arranged in the raised and partially concealed position at the top of the closet.

Fig. 2 is a detailed upper corner view of part of the rack shown in Fig. 1 detached.

Fig. 3 is a sectional view through a closet, diagrammatically illustrating the raised position of the rack in full lines and the lowered use thereof in dot-dash lines.

Fig. 4 is a sectional detailed view illustrating one of the brackets and showing part of the rack in its lowered position in full lines and in raised position in dot-dash lines; and

Fig. 5 is a sectional view through the upper portion of the rack, diagrammatically illustrating arrangement of neckties thereon, the section being substantially on the line 5—5 of Fig. 1.

To illustrate one adaptation and use of my invention, I have diagrammatically illustrated at 10 in Figs. 1, 3 and 4 of the drawing a part of a closet, 11 representing a door opening, controlled in the structure shown by sliding doors, part of one of which is indicated at 12, the doors being slideable on rails, as indicated at 13 in Fig. 4 of the drawing.

The rails 13 are supported in connection with an upper wood frame 14, constituting part of the doorframe and to this frame are secured two left and right brackets 15, 15'. Aside from being left and right, the two brackets are identical. Therefore, the latter brief description of one bracket will apply to both.

As noted in Figs. 1 and 3 of the drawing, within the closet is a shelf 16, below which garments are usually hung and above the shelf is a compartment 17, the forward upper portion of which is usually dead-space that is put to no use whatever.

It is the purpose of my invention to provide an apparel supporting rack 18, which is movably coupled with the brackets 15, 15' and is adapted to be normally stored in the upper compartment 17 of the closet, as diagrammatically seen in Fig. 3 of the drawing, and, then, be

2

lowered to the accessible use position, as noted, for example, in dot-dash lines in Fig. 3.

The rack comprises a main rectangular rod frame 19, to the opposed sides of which are welded or otherwise secured elongated U-frames 20, these frames forming what might be regarded as supporting and guiding rails for support of the rack in raised, as well as lowered positions.

Any type and kind of apparel supporting means can

- 10 be fixed to the frame 19 for support of apparel of different types and kinds. To illustrate one adaptation and use of my invention, I have illustrated two hat supporting loops 21, the loops including rods which extend to and are welded to opposed sides of the frame 19 and one 15 of these rods is illustrated at 22 in Fig. 2 of the drawing. To this rod and the right side of the frame 19 is welded a substantially L-shaped rod 23, which includes a series of crossrod members 24 disposed intermediate the rod 22 and the lower leg 25 of the rod 23.

- 20 Above the rod 22 a pair of necktie supporting members 26 and 27 are welded to the side of the frame 19, the members being in the form of loops having upwardly extending space loop ends 26' and 27', as clearly noted in Fig. 2 of the drawing.

- 25 Considering Fig. 5 of the drawing, it will appear that the member 26 is welded to the lower surface of the frame 19; whereas, the member 27 is spaced above the upper surface of the frame 19 and includes ends that are welded to the inner surface of the side member of 30 the frame, as indicated at 28 in Fig. 2 of the drawing.

- As noted in Fig. 5 of the drawing, neckties can be folded around both of the rods of the members 26, 27 or around each of the rods of such members, the latter being indicated in dot and dash lines in Fig. 5, where 35 parts of neckties 29 and 30 are shown. It will be apparent that the ends of the neckties will lie over the rods 22, 24 and possibly the rod 25 to support the same substantially parallel to the frame 19 when the rack 18 is in either of the positions shown in Fig. 3 of the drawing.

- 40 It will also be noted in Fig. 3 of the drawing that a pair of hats 31 are illustrated as supported in the hat loops 21. The arrangement of the hats and neckties on the rack are omitted in Fig. 1 of the drawing in order to more clearly illustrate the rack structure, but the showings of Figs. 3 and 5 are made in order to illustrate support of articles of apparel upon the rack.

- 45 At this time, it is also pointed out that the rack can be shaped or characterized to support various types and kinds of articles of apparel within the frame structure of 50 the rack.

- 55 Turning now to the supporting brackets 15, 15', the bracket 15 will be specifically described. This bracket comprises a plate 32, having an angularly offset upper portion 33 which, in turn, includes an upstanding angular portion 34, the latter being secured by suitable fastening means to the frame 14, as indicated by the screw 35. The plate 32 has, at its upper inner portion, a grooved pin 36, in which the frame 20 is arranged, the grooving 60 of the pin thus establishing a definite coupling of the rack, preventing displacement or detachment from the closet after the installation or hanging.

- 65 On the plate 32 are inwardly extending pins 37, 38 and 39, which also operate in conjunction with the frames 20 to support the rack in raised concealed position, as well as lowered accessible position and also to guide the rack in its movement from one position to the other. The three pins serve to guide the rack in swinging upwardly from the lowered to the raised position, as will be apparent from a consideration of Fig. 4 of the drawing. The pin 37 keeps the frame 20 in close proximity to the grooved pin 36; whereas, the pins 38 and 39

avoid excessive swinging of the rack in the operation of raising the same. However, when fully raised, the weight of the apparel supported upon the rack will cause the upper end of the rack to swing downwardly and this downward swinging movement is checked by the pin 37.

While the rack would be self-supporting in this position, it is also preferable that the pin 38 be so arranged as to be in alinement with the frames 20, so as to prevent accidental vibratory downward movement and this is clearly noted in the dot and dash showing of the rack 18 in Fig. 4 of the drawing. From this position, when it is desired to lower the rack, the lower rail of the frame 19 is grasped and the lower portion of the rack is forcibly swung inwardly in order to clear the pin 38, after which the rack can be lowered to the full line position, which is partially indicated in Fig. 4 of the drawing and, in this position, the rack is supported by the pin 36 and the pin 39, the pin 39 controlling the angularity of the rack when in its lowered position.

Having fully described my invention, what I claim as new and desire to secure by Letters Patent is:

1. A bracket for movably supporting and guiding racks of the character described, said bracket comprising a plate having an integral angularly extending portion at one surface and edge thereof, said portion including an angularly extending part, the plate having, on said surface, a plurality of spaced guide and stop pins for engaging a rack in movement relatively to the bracket, and at least one of said pins being grooved.

2. A bracket for movably supporting and guiding racks of the character described, said bracket comprising a plate having an integral angularly extending portion at one surface and edge thereof, said portion including an angularly extending part, the plate having, on said surface, a plurality of spaced guide and stop pins for engaging a rack in movement relatively to the bracket, at least one of said pins being grooved, and one of the other pins being disposed in close proximity to said grooved pin.

3. The combination with a closet having a door opening, a shelf at the upper rear portion of the closet adjacent the top of the door opening and a compartment at the top of the closet above said shelf, of an open-work rack, a pair of brackets secured to the closet at sides and exposed at the door opening, said rack comprising a rectangular main rod frame, U-shaped rails at sides of the main frame, said main frame having spaced rod means for supporting articles thereon, and each of said brackets having a plurality of spaced and alined pins engaged by said U-shaped rails for guiding and supporting the rack in movement from a stored position in said top compartment to a lowered position in said door opening.

4. The combination with a closet having a door opening, a shelf at the upper rear portion of the closet adjacent the top of the door opening and a compartment at

5 the top of the closet above said shelf, of an open-work rack, a pair of brackets secured to the closet at sides and exposed at the door opening, said rack comprising a rectangular main rod frame, U-shaped rails at sides of the main frame, said main frame having spaced rod means for supporting articles thereon, each of said brackets having a plurality of spaced and alined pins engaged by said U-shaped rails for guiding and supporting the rack in movement from a stored position in said top compartment to a lowered position in said door opening, and said means comprising a plurality of shaped rods welded to the main rod frame and forming article supporting members.

10 5. The combination with a closet having a door opening, a shelf at the upper rear portion of the closet adjacent the top of the door opening and a compartment at the top of the closet above said shelf, of an open-work rack, a pair of brackets secured to the closet at sides and exposed at the door opening, said rack comprising a rectangular main rod frame, U-shaped rails at sides of the main frame, said main frame having spaced rod means for supporting articles thereon, each of said brackets having a plurality of spaced and alined pins engaged by said U-shaped rails for guiding and supporting the rack in movement from a stored position in said top compartment to a lowered position in said door opening, each of said brackets comprising a plate having angularly extending supporting portions, and at least one of the pins of each bracket being grooved to receive said rails.

15 6. The combination with a closet having a door opening, a shelf at the upper rear portion of the closet adjacent the top of the door opening and a compartment at the top of the closet above said shelf, of an open-work rack, a pair of brackets secured to the closet at sides and exposed at the door opening, said rack comprising a rectangular main rod frame, U-shaped rails at sides of the main frame, said main frame having spaced rod means for supporting articles thereon, each of said brackets having a plurality of spaced and alined pins engaged by said U-shaped rails for guiding and supporting the rack in movement from a stored position in said top compartment to a lowered position in said door opening, each of said brackets comprising a plate having angularly extending supporting portions, and at least one of the pins of each bracket being grooved to receive said rails, another pin of each bracket being arranged adjacent the grooved pin, and the other pins of each bracket supporting the rack in stored and lowered positions.
